[57] CLAIM

The ornamental design for a twist box, as shown and described.

DESCRIPTION

FIG. 1 is a side elevational view of a twist box showing my new design;

FIG. 2 is a top isometric view thereof;

FIG. 3 is a top isometric view thereof, shown in an alternative position;

FIG. 4 is a top isometric view thereof, shown in a further alternative position;

FIG. 5 is a top plan view thereof; and,

FIG. 6 is a bottom plan view thereof.

The broken line showing of a bottle is for illustrative purposes only and forms no part of the claim.
